Primary Examiner — Karen E Eldridge Powers(74) *Attorney, Agent, or Firm* — McCay & Associates, P.C.(57) **CLAIM**

The ornamental design for a pocketed cap, as shown and described.

DESCRIPTION

FIG. 1 is a perspective view of a pocketed cap showing my new design, wherein the edge of the pocket is pulled away from the wall of the crown so that the opening of the pocket is visible;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The gloves shown in broken lines illustrate environmental structure that forms no part of the claimed design. The cross shown in broken lines in FIG. 7 is a feature of the article to which the design is applied that is unclaimed.
